UNITED STATES PATENT OFFICE

DONALD S. BARROWS, OF ROCHESTER, NEW YORK, ASSIGNOR TO THE SYMINGTON COMPANY, OF NEW YORK, N. Y., A CORPORATION OF MARYLAND

FOLLOWER BLOCK

Application filed May 16, 1927. Serial No. 191,723.

This invention relates to railway draft rigging and, more particularly, to a follower block adapted to be positioned between the butt of a coupler and the front end of an associated draft gear for transmitting forces therebetween and providing means for connecting the draft gear with the underframe of the car.

The principal object of my invention, generally considered, is to provide a follower block for railway draft rigging in which the end walls thereof are connected together by a hollow structure which is adapted to directly transmit forces from one end wall to the other, said structure being preferably formed as a longitudinally extending hollow prism, the walls of which, however, may be slightly inclined longitudinally, if desired, giving a frusto-pyramidal effect, certain of said walls being preferably inclined transversely and desirably curved so that said structure may be approximately cylindrical or frusto-conical.

An object of my invention is to provide a follower block for railway draft rigging in which the front and rear walls thereof are joined by a hollow approximately cylindrical web for rigidifying the structure thereof for properly transmitting forces between said front and rear walls.

Another object of my invention is to provide a follower block having front and rear walls joining a hollow approximately cylindrical structure meeting intermediate portions of said walls, said structure being interrupted to provide a transversely extending slot for receiving an associated draft key.

A further object of my invention is to provide a follower block for railway draft rigging comprising end walls and side walls connecting said end walls, said side walls being joined by a webbed portion providing a slot for the reception of an associated draft key, said slotted portion being expanded, intermediate the sides of the block, to provide a hollow approximately cylindrical structure joining said end walls for properly reinforcing said block.

Other objects and advantages of the invention relating to the particular arrange-

ment and construction of the various parts will become apparent as the description proceeds.

Referring to the drawings illustrating my invention, the scope whereof is defined by 55 the appended claims:

Figure 1 is a side elevation, partly in longitudinal section, showing a follower block embodying my invention; the butt of an associated coupler, the front end of an associated cushioning device, and an associated draft key being illustrated diagrammatically by 60 dot and dash lines.

Figure 2 is an end elevation, partly in section, of the follower block on the line 2—2 of 65 Figure 1.

Figure 3 is a plan of said follower block, shown partly in section, on the line 3—3 of Figure 1.

Figure 4 is a fragmentary sectional view 70 corresponding to Figure 2, but showing a slight modification.

Figures 5 and 6 are fragmentary views corresponding, respectively, to Figures 1 and 2, but showing another modification. 75

Figures 7 and 8 are fragmentary views, corresponding, respectively, to Figures 1 and 2, showing a further modification.

Figures 9 and 10 are fragmentary views, corresponding, respectively, to Figures 1 and 80 2, showing a still further modification.

Figures 11 and 12 are fragmentary views, corresponding, respectively, to Figures 1 and 2, showing an additional modification.

Figures 13 and 14 are fragmentary views, 85 corresponding, respectively, to Figures 1 and 2, showing still another modification of my invention.

Figure 15 is a fragmentary view corresponding to Figure 2 and showing a still 90 further embodiment of my invention.

Referring to the drawings in detail, like parts being designated by like reference characters, and first considering the embodiment of my invention illustrated in Figures 95 1, 2 and 3, there is shown a front follower block 1, the front end of which is adapted for engagement with the butt of a coupler 2, indicated diagrammatically by dot and dash lines, and the rear face or wall of which is 100

adapted to engage the front end of a draft gear or cushioning device 3, indicated diagrammatically by dot and dash lines. The follower block 1 is provided with a transversely extending slot 4, adapted to receive a draft key 5, indicated diagrammatically by dot and dash lines. Such a block is adapted for use with Farlow two-key or three-key draft rigging such as illustrated, for example, in the Patent No. 1,126,663 to T. H. Symington or in the Patent No. 841,757 to I. O. Wright et al. but, it is to be understood that my invention is not limited to such forms of draft rigging nor is it limited to use as a front follower for, upon slight modification, for example such as suggested in the Patent No. 1,293,300 to D. S. Barrows, it may be utilized as a rear follower.

Considering the drawings, it will be seen that the front end of the block must resist the load from the relatively small butt of the coupler and, as said coupler angles in every direction, there is applied to the front end of the block, when the coupler is under buff, concentrated loads which successively but irregularly act on the front wall of said block along the path of an approximate circle. On the rear wall of the block, the entire buffing load frequently has to be resisted where said wall engages the small end of an associated draft gear or cushioning device which is properly considered in the form of a relatively small circle, which circle may approximate the circle upon which the buffing force from the coupler is applied.

In order to properly take care of the forces which are required to be transmitted through the block in accordance with the foregoing explanation, I have provided for the substantially direct transmission of said forces from one end wall to the other. A preferred embodiment of the invention comprises utilizing a longitudinal hollow substantially cylindrical web connecting the front and rear walls of the block, interrupted, however, at its sides to provide a slot for the passage of an associated draft key. The walls of this cylindrical structure may be an expansion of the walls which provide the slot or they may be superimposed on said walls above and below the same but preferably involve an expansion of said walls rather than a superpositioning thereon because of the difficulty of securing and venting the segmental cores necessary in the case of superpositioning. My invention, however, is not limited to the use of a hollow cylindrical web as any practical structure, approximating a circular or multi-sided prism, certain of the walls of which are inclined transversely of the block, may be employed instead of a hollow cylindrical structure. If desired, and especially when the engaging ends of the coupler and cushioning device are much different in size, the structure 65 may be frusto-conical or frusto-pyramidal

so that the junctions between the connecting structure and the end walls of the follower block approximately underlie, respectively, the peripheries of the engaging coupler and cushioning device.

With the above considerations in mind, it will be seen that the form of follower block illustrated in Figures 1, 2 and 3 involves a front wall 6, the front face of which, when the block is adapted for use as a front follower, is preferably provided with a forwardly extending coupler-engaging and centering lug 7 of any usual or desired character, and a rear wall 8. Connecting the vertical or side edges of the walls 6 and 8 are side walls 9 and 10, said side walls, in turn, being preferably connected by a hollow webbed structure 11 in which the slot 4 is provided. The follower block is advantageously, although not necessarily, provided with a top wall or web 12 and a bottom wall or web 13, said walls, in the present embodiment, diverging slightly from the front wall 6 to the rear wall 8, as illustrated particularly in Figure 1.

For rigidifying the block and providing for the more direct transmission of forces between the walls 6 and 8 thereof, a hollow structure 14 is provided extending longitudinally of the block between the walls 9, 10, 12 and 13 thereof and joining intermediate portion of said end walls. Said structure, in the present embodiment, is substantially cylindrical except that portions thereof are omitted for permitting the slot 4 to be continuous between the side walls of the block. The sides of the cylindrical structure 14, therefore, merge with the adjacent portions of the transverse hollow structure 11 as indicated at 15.

The upper and lower portions of the cylindrical structure 14 are preferably braced and connected to the upper and lower webs 12 and 13, respectively, by preferably vertical webs 16. Longitudinally extending preferably vertical webs 17 are desirably provided intermediate the webs 16 and the side walls of the block, whereby said top and bottom walls, said transverse webbed structure 11 and said longitudinal approximately cylindrical reinforcement 14 are rigidly tied together. In order to provide for core-removal and lighten the weight of the casting 1, the side walls 9 and 10 are preferably apertured above and below the slot 4 as indicated at 18 and the intermediate webs 17 are correspondingly apertured as indicated at 19. Although the webbed structure 11 is discontinued after it joins with the cylindrical reinforcement 14, yet those portions of said structure, adjacent the ends of the slot 4, are preferably continued the full width of the block 1 as indicated at 20.

Referring now to the embodiment of my invention illustrated in Figure 4, a follower

block is there shown which may be identical with that illustrated in Figures 1, 2 and 3 except that two webs 16^a are employed connecting the cylindrical structure 14^a with the top and bottom walls rather than merely a single web 16 as previously disclosed. Inasmuch as Figure 4 only shows the top half of the casting, there is illustrated only the top wall 12^a, the top portion of the transverse slotted hollow web 11^a, the side walls 9^a and 10^a and the front wall 6^a. It will be noted that, in substituting two connecting webs 16^a for the one web, that portion of the longitudinally extending cylindrical reinforcement 14^a between said webs is omitted to facilitate core-removal. As in the previous embodiment, intermediate longitudinally extending vertical webs 17^a may be provided, said walls 9^a and 10^a and the webs 17^a being apertured as indicated at 18^a and 19^a for a similar purpose.

25 Referring now to the embodiment of my invention illustrated in Figures 5 and 6, a construction identical with that of the embodiment illustrated in Figures 1, 2 and 3 is shown except that the reinforcement 14^b connecting the front wall 6^b and the rear wall 8^b is approximately frusto-conical rather than cylindrical, that is, the upper 30 section thereof slopes to correspond with the top walls 12^b and the lower section (not shown) is correspondingly sloped. Except as specifically described, the construction of the present embodiment may be identical with 35 that of the first embodiment.

53 Referring now to the embodiment of my invention illustrated in Figures 7 and 8, a construction is there disclosed which is identical with that shown in Figures 1, 2 and 40 3 except that the cylindrical reinforcing portion is replaced by a hollow four-sided prism of prismoidal web 14°, the walls of said structure preferably extending at an angle of forty-five degrees with respect to the slotted 45 transverse reinforcement 11° which connects the side walls 9° and 10°. As in the first embodiment, the upper and lower portions of said hollow prism 14° are connected to the upper and lower walls, the upper wall 12° 50 only being illustrated, by means of a web 16°. Except as specifically described, the construction of the present embodiment may be identical with that of the first embodiment.

Referring now to the embodiment of my invention illustrated in Figures 9 and 10, a construction is there disclosed in which a hollow prism 14^a connecting the front wall 6^a and the rear wall 8^a is provided instead of the hollow cylindrical structure 14 of the first embodiment. Said prism 14^a, in the present embodiment, has a top wall 15^a and the side walls are formed by, or merged with, the intermediate longitudinally extending webs 17^a. As in the first embodiment, of course, the side walls of the prism are in-

terrupted by the slot of the transverse reinforcement 11^a and said transverse and longitudinal reinforcements merge together at their intersections, that portion of the transverse reinforcement 11^a, between the side walls of the prism or the intermediate webs 17^a of the follower, being omitted as in the first embodiment. The top and bottom walls of the reinforcing prism 14^a may be, respectively, connected to the top and bottom walls of the follower, the top wall 12^a only of which is illustrated, by longitudinally extending webs 16^a apertured as indicated at 21 to facilitate core-removal and lighten the weight of the casting. Except as specifically described, the construction of the present embodiment may be identical with that of the first embodiment.

Referring now to the embodiment of my invention illustrated in Figures 11 and 12, 85 a construction is there disclosed which is substantially identical with that of the first embodiment except that the transverse slotted reinforcement 11^e is continued through the longitudinal cylindrical reinforcement 14^e and provision for holding and removing the core, between said longitudinal and transverse reinforcements, is made by an aperture 21^e in the longitudinal web 16^e connecting said cylindrical reinforcement 14^e with the top and bottom walls of the follower, the top wall 12^e only being illustrated. 95 This aperture 21^e is continued through the cylindrical reinforcement 14^e as indicated at 22 to provide access to the core space between said reinforcement and the slotted transverse reinforcement 11^e. Except as specifically described, the construction of the present embodiment may be substantially identical with that of the first embodiment. 100 105

Referring now to the embodiment of my invention illustrated in Figures 13 and 14, a construction is there disclosed in which the longitudinal reinforcement 14^f is plus or star-shaped rather than cylindrical or prismoidal as in the other embodiments. That is, said longitudinal reinforcement involves longitudinal webs 14^f which preferably merge, respectively, adjacent the top and bottom of the transverse slotted reinforcement 11^f, flaring upwardly and downwardly to, respectively, intersect and merge with the top and bottom walls of the follower, the top wall 12^f only being illustrated. Said webs 14^f preferably incline at angles of approximately forty-five degrees with respect to said transverse reinforcement 11^f. In the present embodiment, the construction may be considered to correspond with that illustrated in Figures 7 and 8, the walls of the hollow longitudinal prism 14^e there shown being revolved through ninety degrees with the centers of said walls maintained in substantially the same position. In other words, the reinforcing webs 14^f of the present embodiment function sub- 130

stantially like the walls of the hollow prism 14^c of Figures 7 and 8 except that they are inclined at ninety degrees with respect to the inclination of the referred to embodiment.

5 In the present embodiment, the outer ends of the webs 14^f may be considered as merging with the intermediate webs 17^f and the central longitudinal web 16^f does not connect with the reinforcement 14^f. In this case, the 10 reinforcing webs 14^f are preferably apertured, as indicated at 22^f to provide for core-placing and removal. The rear or draft gear engaging end of the follower may be provided with a lug 23 for engaging in a corresponding aperture in the front of the associated cushioning mechanism or draft gear and holding the same in proper assembled relation with respect thereto. It will be appreciated that the employment of said lug 15 20 23 is analogous to that of the lug 7 for coupler engaging purposes and such a lug may be used on any or all of the embodiments of my invention here illustrated or contemplated or all of said embodiments may be unprovided therewith. Except as specifically described, the construction and function thereof may be substantially identical with that of the first embodiment.

Referring now to the embodiment of my 30 invention illustrated in Figure 15, a construction is there disclosed which is substantially identical with that of the first embodiment except that the reinforcement 14^g, connecting the front and rear walls of the casting, is a 35 hollow hexagonal prism rather than a hollow cylinder, that is, the walls of said structure preferably slope from the central longitudinal web 16^g toward the intermediate longitudinal webs 17^g, meeting said latter webs at 40 points above and below the transverse slotted reinforcement 11^g. It will, therefore, be apparent that the only material difference between the embodiment here illustrated and that illustrated in Figures 1, 2 and 3 is that 45 the webs, defining the hollow reinforcement 14^g, are plane and angularly disposed with respect to each other forming a hexagonal prism rather than being curved to form a hollow cylinder. It will be appreciated, however, that said prism may be considered as an 50 approximate cylinder in that the walls thereof follow closely the contour of a cylinder so that it functions in substantially the same manner. The connecting web 16^g, instead of 55 being imperforate, is formed with apertures 21^g above and below the transverse slotted reinforcement 11^g for lightening the weight of the casting and facilitating core-removal. Except as specifically described, the construction 60 of the present embodiment may be identical with that of the first embodiment.

In accordance with the foregoing disclosure, it will be observed that I have provided a form of block which is particularly adapted 65 to efficiently transmit stresses between the

end walls or faces when forces are applied either from the coupler to the front wall thereof or from the cushioning device or draft gear to the rear wall thereof. Of course, the longitudinal intermediate reinforcement, 70 which is preferably cylindrical or approximately cylindrical either in actual contour or in function, is particularly adapted for transmitting forces from one end wall directly to the other but it will be understood that, when draft forces are applied to the gear, said forces are efficiently transferred from the rear wall of the block, through the longitudinal reinforcement, to the transverse slotted reinforcement and, from thence, through the connecting key to the underframe of the car. Although this form of block is peculiarly adapted to the ordinary form of coupler butt, it is also desirable for use with any coupler, for example one having a swivel butt, inasmuch as with increasing severity of service, an increased column area for the direct transmission of stresses is desirable. Although several desirable embodiments of my invention have been illustrated, I do not wish to be limited to the exact features there shown as my invention broadly comprises all forms embodying the spirit of my invention embraced within the scope of the appended claims.

Having now described my invention, I 95 claim:

1. A follower block for railway draft rigging comprising end walls adapted to engage the butt of an associated coupler and the end of an associated cushioning device, and webs extending longitudinally between said end walls and spaced to leave a slot for an associated draft key, said webs, intermediate the sides of the block, being spaced more widely apart so as to more directly transmit stresses between the end walls received, respectively, from the butt of said coupler and the end of said cushioning device.

2. A follower block for railway draft rigging comprising end walls adapted to, respectively, engage the butt of an associated coupler and the end of an associated cushioning device, web portions connecting intermediate parts of said end walls and provided with a slot for the reception of an associated draft key, certain portions of said webs being inclined transversely with respect to said slotted portions for efficiently transmitting stresses between said end walls.

3. A follower block for railway draft rigging comprising end walls adapted to, respectively, engage the butt of an associated coupler and the end of a cushioning device, and webs extending longitudinally between intermediate portions of said end walls, portions of said webs being inclined transversely of the block in order to directly transmit stresses between the end walls thereof.

4. A follower block for railway draft rigging comprising end walls adapted to, respec-

tively, engage the butt of an associated coupler and the end of an associated cushioning device, and an approximately cylindrical structure slotted for receiving a connecting draft key, extending between said end walls and meeting intermediate portions thereof for directly transmitting forces received thereon from one wall to another.

5. A follower block for railway draft rigging comprising end walls adapted to, respectively, engage the butt of an associated coupler and the front end of an associated cushioning device, a hollow approximately cylindrical structure extending between said walls and joining intermediate portions thereof for directly transmitting forces received on one of said walls to the other, said structure being formed with a transverse slot for receiving an associated draft key.

20 6. A follower block for railway draft rigging comprising end walls adapted to, respectively, engage the butt of an associated coupler and the end of an associated cushioning device, side walls extending longitudinally and joining the vertical edges of said end walls, a transverse webbed structure joining said side walls and slotted for the reception of an associated draft key, and a longitudinally extending hollow approximately cylindrical structure connecting said end walls and intersecting said transverse webbed structure intermediate said side walls.

25 7. A follower block for railway draft rigging comprising end walls adapted to, respectively, engage the butt of an associated coupler and the end of an associated cushioning device, top, bottom and side walls extending longitudinally and connecting the corresponding edges of said end walls, and a hollow approximately cylindrical structure extending between and joining with said end walls, at the ends thereof, between said top, bottom and side walls for directly transmitting forces received on said end walls and rigidifying the block.

30 8. A follower block for railway draft rigging comprising end walls adapted to, respectively, engage the butt of an associated coupler and the end of an associated cushioning device, side walls connecting the corresponding edges of said end walls, webs extending substantially parallel to said side walls and connecting intermediate portions of said end walls and additional webs extending diagonally from said first mentioned webs and connecting intermediate portions of said end walls for rigidifying the construction and directly transmitting forces between said end walls.

35 9. A follower block for railway draft rigging comprising end walls, one of which is adapted to engage the end of an associated cushioning device, side walls connecting said end walls and slotted for the reception of an associated draft key, said slotted portions ex-

tending transversely toward the center of the follower and formed with diverging portions adjacent the longitudinal center line thereof, said increased portion being extended longitudinally to the ends of the block for efficiently transmitting stresses therebetween.

40 10. A follower block for railway draft rigging comprising end walls, one of which is adapted to engage the end of an associated cushioning device, and webs extending laterally and longitudinally between said end walls and disposed between the upper and lower edges thereof, each web having a portion between the side edges thereof spaced a greater distance from the other web than the remainder to efficiently transmit forces between the end walls.

In testimony whereof I affix my signature.
DONALD S. BARROWS.
